VACUUM CLEANING NOZZLE

Ake Sigurd Bertil Kramer, Grev Magnigatan 5,
Stockholm, Sweden

Filed Mar. 24, 1971, Ser. No. 127,857

Term of patent 14 years

Int. Cl. D15—05

U.S. Cl. D49—17

FIG. 1.

FIG. 2.

FIG. 3.

FIG. 1 is a side view of the nozzle, positioned for suction having the suction nozzle pointing downwards.

FIG. 2 is a perspective view of the nozzle shown in FIG. 1 but in closed position, having the tubular suction member with the suction nozzle pointing upwards.

FIG. 3 is a perspective view in an enlarged scale of the lower part of the nozzle, said nozzle having the tubular suction member pointing upwards.

I claim:

The ornamental design for a vacuum cleaning nozzle, as shown.
